UNITED STATES PATENT OFFICE.

CLARENCE E. REED, OF HOUSTON, TEXAS.

GRAPPLE FOR OIL-WELLS AND THE LIKE.

1,375,320.

Specification of Letters Patent. Patented Apr. 19, 1921.

Application filed July 21, 1919. Serial No. 312,300.

To all whom it may concern:

Be it known that I, CLARENCE E. REED, a citizen of the United States, and resident of Houston, Texas, have invented certain new and useful Improvements in Grapples for Oil-Wells and the like, of which the following is a specification.

My invention is particularly designed for recovering rigging or parts of rigging lost 10 in oil wells, though it is not limited to such use.

In the drawings:

Figure 1 is a vertical sectional view of the appliance substantially on line 1—1 of 15 Fig. 3 with the parts in their open position ready to be let down into the well.

Fig. 2 is a similar view with the parts in the position assumed by them when closed to grip the object.

20 Fig. 3 is a cross sectional view on line 3—3 of Fig. 1.

Fig. 4 is a bottom plan view.

Fig. 5 shows detail views of one of the 25 spreader members.

Fig. 6 is a cross sectional view on line 6—6 of Fig. 1.

Fig. 7 is a bottom plan view of the jaws.

Fig. 8 is a similar view of a modification.

Fig. 9 shows details of the jaws.

30 The appliance comprises a main tubular part A, which carries a spider or ring C in which are pivoted at D' the grapple jaws D. This tubular member A also carries a finder or contact member P whose screw threaded shank is freely slidable in the tubular member.

This finder has a head F adjustable thereon by its screw thread connection, and this head is connected by links E with the jaws 40 of the grapple.

When the finder strikes the object it is arrested but the main body A continues its downward movement and this causes, by means of rod G, the relative lifting of the 45 member H in respect to the wedge L which normally, is held against vertical movement on the tubular member by the cone B. The collar or member H carries wedge shaped spreader members K, which engage the upper

50 per inwardly curved edges of the upper ends of the jaws D so that these will be spread apart as the member H rises in relation to the jaws, and thus the lower gripping ends of the jaws will be moved inwardly to grip

the object, and this may then be drawn from 55 the well by lifting the appliance.

The spreaders are toothed and the edges of the jaw members are toothed so that when set the parts will be substantially locked in gripping position. To loosen the grapple 60 for removing the recovered body, the cone B is turned and run up or back on its screw thread and then by tapping the wedge L by a suitable implement at the shoulder X the wedge is withdrawn and the spreaders 65 are permitted to recede inwardly and free the jaws from holding or locking pressure.

The cone B acts as a guard to prevent the upper ends of the jaw members D from catching against any protuberance from the 70 wall of the hole.

The jaws as shown in plan view are segments of a tube and the gripper faces are comparatively narrow and are centrally arranged in respect to the segments. This 75 substantially circular form of the gripper jaws enables it to be lowered into or removed from the hole with substantially the same facility as a pipe, and more so, so far as the upper and lower ends are concerned, 80 which are turned inwardly to avoid catching on any projection from the wall of the hole.

The wedge member L is splined to the main body A at M.

The jaws may be of the form shown in 85 Fig. 7, bottom plan view, and may be screw threaded to take hold of a screw threaded pipe, or they may be as shown in Fig. 8, where they overlap resulting in coming closer together.

90 The finder member P may be adjusted in relation to the jaws so that the latter may be made to operate and grip the object at different distances from the point where the finder contacts with the object so that the 95 extent of grip may be regulated to suit the character, thickness or height of the object to be recovered.

The main body A is adapted to be attached to a suspension member. In the particular form illustrated the main body is screw threaded at its upper end for this purpose.

I claim—

1. A grapple for oil wells comprising a 105 main body, a plurality of gripper jaws pivotally connected thereto intermediate of their length at different points about the

same, said jaws being in cross section of curved segmental form to provide a split tube-like body to conform to the bore of the well, a finder arranged coaxially with the 5 segmental jaws, spreader means slidable on the main body and coaxially arranged with and between the upper ends of the jaws, an operating connection between the finder and the spreader means, said main body at its 10 upper end having means for attachment to a suspending member, substantially as described.

2. In combination in a grapple for oil wells, a main body member, jaws pivotally mounted thereon and of segmental cross sectional form, a finder slidably guided on the main body and arranged coaxially with and between the lower ends of the segmental jaws, spreader means supported by the 15 main body between the upper ends of the jaws, a connection between the finder and the spreader means, said main body having means at its upper end for attachment to a suspending device.

25 3. In combination in a grapple for oil wells, a main body, a plurality of jaws pivotally mounted thereon, a centrally arranged finder at the lower end of the main body, spreader means between the upper 30 ends of the jaws, a connection between the finder and the spreader means, and links connecting the finder with the lower parts of the jaws, substantially as described.

4. In combination a main body having 35 means for attachment thereto of a suspending member, gripper jaws pivotally mounted thereon, a finder member relatively slid- 40 able in respect to and guided by the main body and spreader means for the gripper jaws guided by the main body and connected to the finder to be operated thereby, substantially as described.

5. In combination a main body, gripper jaws pivotally mounted thereon, a wedge 45 member on the main body, spreader means for the jaws slidable on the wedge, and a finder to contact with and be arrested by contact with the object to be recovered said finder operating the spreader means, sub- 50 stantially as described.

6. In combination a main body, gripper jaws pivotally mounted thereon, a wedge member on the main body, spreader means for the jaws slidable on the wedge, a finder 55 to contact with and be arrested by contact with the object to be recovered said finder operating the spreader means, and releasable means for holding the wedge, substan- tially as described.

60 7. In combination a main body, gripper jaws pivotally mounted thereon, a wedge member on the main body, spreader means for the jaws slidable on the wedge, a finder to contact with and be arrested by contact 65 with the object to be recovered said finder

operating the spreader means and releasable means for holding the wedge, said releasable means comprising a guard to shield the gripper jaws from catching on the wall of the hole, substantially as described.

8. In combination a main body of tubular form, a finder member relatively slidable in said tubular body, gripper jaws pivoted to the body and spreader means relatively slid- 75 able on the body and a connection between the finder and the spreader means for operating the latter, said connection including a cap or head having a screw threaded connection with the finder and slidably engag- 80 ing the tubular body, substantially as described.

9. In combination a main body, jaws pivoted thereto, spreader means, a wedge splined on the main body for setting the spreader means, and a collar screw threaded 85 on the main body for holding the wedge, said wedge being movable when released by adjusting the collar.

10. In combination a main body having means for attachment thereto of a suspending member, gripper jaws pivoted thereto and having toothed upper ends, slidable spreader means toothed to engage the teeth of the jaws, means for operating the spreader comprising a wedge member and 95 means for releasing the wedge means, sub- stantially as described.

11. In combination in a grapple of the class described, a main body, movable wedge means thereon, spreader members movable 100 along the wedge means, thereby to be moved radially in respect to the axis of the main body, a carrier for said spreader members, jaws borne upon by the spreader members and a finder to contact with the article to 105 be recovered, said finder operating the said carrier, substantially as described.

12. In combination in a grapple of the class described, a main body, movable wedge means thereon, spreader members movable 110 along the wedge means, thereby to be moved radially in respect to the axis of the main body, a carrier for said spreader members, jaws borne upon by the spreader members and a finder to contact with the article to 115 be recovered, said finder operating the said carrier, and releasable means for holding the wedge whereby the latter may be released to move on the main body for releasing the spreader members, substantially as 120 described.

13. In combination in a grapple of the class described, a main body member, a ring carried thereby, jaws pivotally mounted on the ring, a carrier member slidably mounted to move longitudinally of the main body, spreader means for the jaws mounted in the carrier, wedge means on the main body for causing outward radial movement of the 125 spreader means, a finder and a connection 130

between said finder and the carrier, substantially as described.

14. In combination in a grapple of the class described, a tubular main body portion, jaws pivotally mounted at a point intermediate of their length and supported by the main body portion, spreader members engaging the upper ends of the jaws at points above their pivots, carrier means for the spreader members, wedge means on the

main body for causing radial movement of the spreader members as they traverse the said wedge means, a finder guided in the tubular body at its lower end and a connection between said finder and the carrier, substantially as described. 15

In testimony whereof, I affix my signature.

CLARENCE E. REED.
